UNITED STATES PATENT OFFICE.

WILLIAM M. DUNCAN, OF ALTON, ILLINOIS.

TRAVELING-GRAVE STOKER.

1,395,486.

Specification of Letters Patent.

Patented Nov. 1, 1921.

Application filed April 17, 1919. Serial No. 290,665.

To all whom it may concern:

Be it known that I, WILLIAM M. DUNCAN, a citizen of the United States of America, and a resident of Alton, in the county of 5 Madison, State of Illinois, have invented certain new and useful Improvements in Traveling-Grate Stokers, of which the following is a full, clear, and exact description, reference being had to the accompanying drawings, forming a part of this specification.

My invention relates to improvements in traveling grate stokers, the invention having for its object the production of a grate of this 15 type in the use of which the following points of merit are attained, viz., the avoidance of loss of fine fuel through the air passages in the grate; increased air space for the support of combustion; and an arrangement at the top surface of the grate whereby the fuel 20 deposited upon the grate, is deflected upwardly at an incline relative to the direction of travel of the grate to facilitate the passage of air into the fuel as the air ascends through the grate. Other features of novelty 25 in my grate will be hereinafter pointed out and fully described in addition to those here enumerated.

Figure I is a longitudinal section through the forward portion of an endless chain 30 grate having my invention incorporated therein, and other portions of a mechanical stoker with which the chain grate is associated.

Fig. II is an enlarged top view of one of 35 my links.

Fig. III is a side elevation of one of the links.

Fig. IV is an end view.

Fig. V is a vertical cross section taken on 40 line V—V, Fig. III, through the upper portion of the link.

In Fig. I of the drawings I have shown a collection of my links incorporated in the traveling chain grate A of mechanical 45 stoker, the stoker also including a frame B, a grate driving member C shown in the form of a sprocket wheel fixed to the shaft D and by which the chain grate is driven in the direction indicated by the arrow. The stoker 50 also preferably includes a hopper E from which coal or other fuel is delivered to the grate as is usual in the operation of mechanical stokers.

The traveling chain grate comprises rows 55 of grate links F connected together by means

of pivot rods G, as is well understood in this art. Each of the grate links I have shown comprises a web 1 provided with hollow bosses 2 in which the pivot rods are mounted. In the preferred form of the invention 60 the web 1 is formed with a wedge-shaped top margin 3, the relatively sharp edge being at the top of the web, and a longitudinal row of fuel supporting ribs or tongues 4 extending laterally from opposite sides of said 65 wedge-shaped top margin to form the fuel supporting top of the link. The fuel supporting tongues are separated from each other to provide open draft passageways at opposite sides of the wedge-shaped top margin 70 3. By combining these fuel supporting tongues with the sharp upper margin of the web 3, I provide for the delivery of air to almost all of the fuel resting upon the top of the grate link. These draft passageways 75 extend approximately from one side of the fuel supporting surface to the other, for the sharp upper margin 3 does not materially interfere with the delivery of the draft to the fuel above the longitudinal center line of the grate link. The entire upper margin of the grate link is therefore cooled by the rising air currents, and combustion is very materially facilitated by the delivery of air to all of the fuel on the grate.

The fuel used with mechanical stokers having grate links of the type herein shown, is usually fine coal, and although the many draft passageways are open at the top for the delivery of air to approximately all of 80 the fuel, I desire to prevent the fine fuel from dropping through these draft passageways. The upper portions of the fuel supporting tongues 4 are, therefore, extended upwardly at an angle, so as to overlie the 85 draft passageways between said tongues. If desired, the tongues 4, which extend over the sharp upper edge of the wedge-shaped portion 3, may overlap each other as shown in Fig. III. By extending the fuel supporting 90 tongues in this manner, I prevent fine coal from dropping freely through the draft passageways, and at the same time enable the draft to pass freely through the open top of the grate link.

It is likewise important to observe that the top faces of the fuel supporting tongues 4 are inclined upwardly from the open upper ends of the draft passageways. When a grate link is traveling under the fuel inlet at 100 105 110

the bottom of hopper E (Fig. I) the link must form a support for fuel in the hopper, and at this time the top face of the grate will slide, to a certain extent, on the bottom face of the body of fuel. Whenever this action occurs, the inclined top faces of the tongues 4 will deflect the fuel upwardly and away from the draft passageways, as suggested by the dotted line X in Fig. III. The fine coal at 10 the bottom of the hopper E is usually hot and it tends to lie in a compact mass, so this coal will be readily deflected under the conditions just pointed out, to form small arches over the draft passageways, approximately 15 as indicated by the dotted line X. Of course, such arches will not be perfectly formed, but the inclined top faces of the fuel supporting tongues 4 will readily deflect the relatively stationary coal upwardly and away from the 20 draft passageways. The coal is thus prevented from being forced through, or scraped into, the draft passageways when the grate link passes under the fuel inlet. Note that the top faces of the fuel supporting 25 tongues 4 are inclined upwardly in a direction opposite to the direction of travel of the grate. If a grate link was reversed, end for end, its tongues 4 would tend to scrape the fine fuel from the hopper E and into the 30 draft passageways, instead of performing the useful function of deflecting the fuel away from said passageways.

If the bottom face of the fuel would be arched, as shown at X in Fig. III, between 35 all of the adjacent tongues 4, an ideal condition would be obtained, and the draft would be most effectively delivered to all of the arched faces. However, some of the coal and ashes will eventually slip downwardly 40 on the inclined top faces of tongues 4, and as a further precaution to prevent this fine material from dropping through the draft passageways, pockets 7 may be formed at the lower ends of the inclines on said top 45 faces. These pockets, or the like, are preferably formed at the open upper ends of the draft passageways, so as to prevent free slippage of material at the lower ends of the inclines.

50 I claim :

1. In a mechanical stoker provided with a fuel inlet, a traveling grate comprising grate links movable under said fuel inlet, each of said grate links comprising a web having at 55 its top margin a longitudinal row of fuel supporting tongues which extend laterally from said top margin to form the fuel supporting top of the link, said fuel supporting tongues being separated from each other to 60 provide a longitudinal row of draft passageways between them, and said row of fuel supporting tongues being provided with extensions having inclined top faces for deflecting the fuel away from the open upper 65 ends of said draft passageways, the inclina-

tion of said faces being upwardly in a direction opposite to the direction of travel of the grate.

2. In a mechanical stoker provided with a fuel inlet, a traveling grate comprising grate 70 links movable under said fuel inlet, each of said grate links comprising a web having at its top margin a longitudinal row of fuel supporting tongues which extend laterally from said top margin to form the fuel supporting top of the link, said fuel supporting tongues being separated from each other to provide draft passageways between them, the top faces of said fuel supporting tongues being provided with fuel retarding pockets 75 at the open upper ends of said draft passageways, and said top faces being inclined upwardly from said pockets in a direction opposite to the direction of travel of the grate, whereby the fuel is deflected away 80 from said upper ends of the draft passageways.

3. A mechanical stoker provided with a fuel inlet, a row of traveling grate links movable under said fuel inlet, each of said 90 grate links comprising a web having at its top margin a longitudinal row of fuel supporting tongues which extend laterally from said top margin to form the fuel supporting top of the link, said fuel supporting tongues 95 being separated from each other to provide a longitudinal row of draft passageways between them, the upper margins of said longitudinal row of fuel supporting tongues being extended upwardly at an angle so as 100 to overlie the open upper ends of said longitudinal row of draft passageways, and said fuel supporting tongues being provided with inclined top faces for deflecting the fuel away from said open upper ends of the 105 draft passageways, the inclination of said top faces being upwardly in a direction opposite to the direction of travel of the grate.

4. A mechanical stoker provided with a 110 row of traveling grate links, each of said 115 grate links comprising a web having a wedge-shaped top margin, the substantially sharp edge being formed longitudinally of and at the top of the web, and a longitudinal row of fuel supporting tongues extending laterally from opposite sides of said wedge-shaped top margin to form the fuel supporting top of the link, said fuel supporting tongues being separated from each other to 120 provide draft passageways between them at opposite sides of said wedge-shaped top margin, the upper portions of said fuel supporting tongues being extended upwardly and over said sharp edge, so as to overlie 125 said draft passageways, and said fuel supporting tongues being provided with inclined top faces which extend upwardly from the open upper ends of said draft passageways.

5. In a mechanical stoker provided with a fuel inlet, a row of traveling grate links movable under said fuel inlet, each of said traveling grate links having, at its top margin, a longitudinal row of fuel supporting tongues which extend laterally from said top margin to form the fuel supporting top of the link, said fuel supporting tongues being separated from each other to provide 5 a longitudinal row of open draft passageways between them, said fuel supporting tongues being provided with extensions pro-
jecting over the open upper ends of said draft passageways so as to overlie the row of open ends, and said extensions being provided with inclined top faces for deflecting the fuel from the open upper ends of said draft passageways, and the inclination of said top faces being upwardly in a direction opposite to direction of travel of the grate 15 links.
- 10 In testimony that I claim the foregoing I hereunto affix my signature.

WILLIAM M. DUNCAN.
